UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed June 10, 1925. Serial No. 36,088.

To all whom it may concern:

Be it known that I, MELVIN L. STONE, a citizen of the United States, and a resident of Lawrence, in the county of Essex and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms whereby the operative condition of the loom is changed from time to time, as by replenishment of filling.

Feeler mechanisms now in general use provide a feeler which is normally under the influence of means tending to move it to rearward feeling position, and when the feeler is performing its feeling function on a detecting beat, the full impact of the feeler is exerted against the filling in the shuttle, with the result that the filling is injured and such injury is especially noticeable in some characters or kinds of filling.

One of the objects of the present invention is to provide a feeler mechanism wherein the feeler shall be given an initial frontward movement on a detecting beat by means independent of the filling, to the end that the filling may engage the feeler during its initial frontward movement and thereby be relieved of injurious contact by the feeler, which may thereafter act in the usual manner common to feeler mechanisms for effecting a change in loom operation when substantial exhaustion of the filling is detected in the shuttle.

The invention, novel features and new combination of parts will best be made clear from the following description and the accompanying drawings of one good practical form thereof.

In the drawings:

Fig. 1 is a perspective view at the feeler side of a loom provided with the present invention;

Fig. 2 is an enlarged perspective view, showing more particularly the construction of a feeler having an impinging and a penetrating member with which the present invention may be advantageously employed;

Fig. 3 is a sectional side elevation of a feeler mechanism having an impinging and

penetrating member and the means for imparting the initial frontward movement to the feeler; and

Fig. 4 is a similar side elevation of a feeler mechanism of the measuring type, having associated therewith the present invention.

Feeler mechanisms are now generally employed to effect replenishment of filling when that in the active shuttle becomes substantially exhausted, and the present invention is shown in connection with such general mechanism, but it is to be understood, of course, that the feeler mechanism may act through a train of devices for effecting other changes in the loom operation, such as stopping the loom, for instance. The replenishing mechanism is not herein illustrated and described because the details thereof form no essential part of the present invention and are now well understood in the art.

The loom frame 1 may be of useful construction for supporting the operating parts, and is herein shown as provided with bearings 2, one at each side of the loom, for the usual transverse or rock shaft 3 which controls the operative condition of the replenishment mechanism, as usual. Extending upwardly from the rock shaft 3 is an arm 4 having pivotally associated therewith at 5 a rearwardly extending arm 6 or actuator 6, the rear end portion 7 of which is adapted to be engaged at times by an operating member 8 which may be conveniently formed as or secured to the cam follower.

Pivottally mounted on the shipper stand 9 at 10 is an arm 11, the end 12 of which extends beneath the actuator 6 as shown. The arm 11 has extended therefrom at the other side of its pivotal support, an arm 13 provided with a cam portion 14 over which extends the transmitter 15 which may be constituted as an arm pivotally mounted at 16 and normally under the influence of a spring 17 for holding the transmitter in its rearward normal position. The mechanism so far described may be varied in construction but as shown constitutes one good practical form of means under control of the feeler mechanism for effecting replenishment of filling.

The preset invention may be advantageously employed in connection with any type of feeler mechanism, and, as shown in Figs. 1, 2 and 3, the feeler mechanism is of the impinging and penetrating type, while in Fig. 4 the feeler mechanism is of the measuring type, the two forms being herein shown to demonstrate the universal application of the present invention to feeler mechanisms of any type.

The shipper stand 9 has extending therefrom a support 18 to which may be adjustably secured a bracket 19 for the support of a feeler stand 20 on which the feeler itself is mounted.

The feeler, as indicated in Fig. 1, comprises the slide 21, the forwardly extending stem 22 of which is normally under the influence of a spring 23 for moving the feeler to its rearward feeling position.

The lay 24 may be of usual construction and provided with a shuttle box 25, the front wall of which is provided with an opening 26 which registers with a similar opening 27 in the shuttle 28 when the latter is in the shuttle box, the construction being such that the feeler, regardless of the type, may enter the shuttle on a detecting beat and detect the condition of the filling therein.

As shown in Fig. 1, the feeler comprises an impinging and a penetrating member, the former of which is normally locked in its rearward filling engaging position to prevent contact of the penetrating feeler with the filling until near approach to substantial exhaustion and thereupon is unlocked to permit the penetrating feeler to act and call for a change in filling when that in the shuttle is substantially exhausted. More in detail, the feeler slide 21 is extended rearwardly, as at 29, and has mounted in the rear extension 29 the yoke 30, the two side arms 31 of which project rearwardly through openings in the rear extension 29, and at their ends are provided with yielding or rubber buffers 32. The yoke 30 is normally under the influence of a spring 33 which tends to move the yoke rearwardly to project the buffers 32 beyond the rear end of the feeler, and when in such projected position the impinging member of the feeler is locked by a pin 34 carried by an arm 35 mounted for rocking movement on the cross-shaft 36 carried by the feeler. The arm 35 has an upwardly extending portion 37, the rearwardly extending end 38 of which carries an adjustable bunter 39, the construction being such that when the feeler enters the shuttle a sufficient amount due to the gradual depletion of the filling therein, the bunter 39 may be struck by a surface on the lay, such as the front wall of the shuttle or shuttle box, and unlock the yoke 30, so that

it is then free for forward movement under the pushing influence of the filling in the shuttle.

Pivotaly mounted on the shaft 36 is the forwardly extending arm 40 the dovetailed end portion 41 of which is adapted at times to engage the transmitter 15 to initiate replenishment of filling.

Secured to the arm 40 is the adjustable stud 42, Fig. 2, which carries the penetrating member 43 of the feeler, the penetrating end 44 of which is normally restricted with respect to the buffers 32 during normal weaving operations.

From the construction described as one good practical form of a penetrating feeler that may be employed in connection with the present invention, it will be noted that during weaving with a working supply of filling present in the shuttle, the buffers 32 will engage the filling until, when the filling approaches near substantial exhaustion, the bunter 39 will strike a surface on the lay, unlock the yoke 30 and permit the buffers 32 to yield forwardly relative to the feeler, whereupon, the penetrating member of the feeler will act to call the change when the filling is substantially exhausted.

In accordance with the present invention, the feeler, whether it be of the penetrating or other type, is to be given a forward initial movement just prior to its engagement with the filling, and is to thereafter engage the filling while the feeler itself is being moved forwardly, the result being that the injurious contact of the feeler with the filling is avoided.

As more clearly indicated in Figs. 1 and 2, the feeler slide has secured thereto and extending downwardly therefrom, as shown, a projection or arm 45 which is consequently movable with the feeler. Secured to the loom frame, or, as shown, to an arm extending from the shipper stand, is an adjustable bracket 46 which may be appropriately secured in place by screws 47, and mounted on the rear portion of the bracket 46 is a stud or dead shaft 48 on which is mounted a cam 49 adapted to be engaged by the lower end portion 50 of the projection or arm 45 connected to the feeler, when the feeler is in its rearward feeling position, as indicated in Fig. 1.

The cam 49 has connected thereto an arm 51 to which is adjustably secured a bunter 52 which may be held in adjusted position as by nuts 53, 54. The bunter 52 is adapted to be actuated from a going part of the loom to turn the cam 49 just prior to engagement of the feeler with the filling, with the result that the feeler itself will be given an initial forward movement and will during such forward movement be gently engaged by the filling in the shuttle.

In the present instance, the bunter 52 is

adapted to be engaged by the lay 24 to thereby turn the cam 49 and move the feeler frontwardly during a detecting beat and just prior to engagement of the feeler with the filling, the construction of parts being such that as the cam is turned to impart the initial frontward movement to the feeler, the filling itself is moved frontwardly due to lay movement, but at a higher rate of speed than the feeler itself, so that during the frontward initial movement of the feeler, the filling will engage the feeler and continue its frontward movement, that the feeler may act to call the change if conditions warrant it.

In the feeler construction shown by Fig. 4, the feeler is of the measuring type, that is, the feeler slide has its rear portion 55 mounted for engagement with the filling, and pivotally mounted on the feeler slide at 56 is the frontwardly extending arm 57 having adjustably secured thereto a bunter 58 adapted to be engaged by the wall of the shuttle or shuttle box when the feeler detects substantial exhaustion of the filling, to thereby position the arm 57 for engagement with the transmitter 15 and effect a change in the loom operation. The feeler construction last described may be of usual character and associated therewith is the downwardly extending arm 45 which cooperates with the cam 49 through the bunter 52 on a detecting beat to start the feeler frontwardly just prior to its engagement with the filling, as indicated by dotted lines in Fig. 4, so that as the lay continues its frontward movement, the filling will engage the feeler during the frontward movement thereof which is being imparted to it through the cam 49 and projection or arm 45.

It may be desired at times to limit the throw of the cam 49 and to this end the bracket 46 has a stop shoulder 59 which may be engaged by a pin 60 projecting from the cam 49 when the lay is in back position and the parts are related as shown in Fig. 1. Likewise, it may be desirable at times to prevent overthrow of the cam 49 by the lay, especially in high speed looms, and to this end the bracket 46 has another stop 61 against which the pin 60 may strike as the lay moves forward under high speed, should the bunter upon it overthrow the cam movement. As the lay goes back, of course the weight of the arm 51 and bunter 52 will carry the cam to its initial position, as indicated in Fig. 1 and by dotted lines in Figs. 3 and 4.

From the construction described as one good practical form of the present invention, it will be apparent that on a detecting beat of the lay, the latter will engage the bunter 52 prior to the engagement of the feeler with the filling and by turning movement of the cam 49 will act upon the pro-

jection or arm 45 to move the feeler frontwardly at a speed dependent upon the contour of the cam which should be such that the frontward initial movement of the feeler is somewhat less than the frontward movement of the lay or filling in the shuttle, with the result that as the lay beats up, the filling will engage the feeler during the initial frontward movement of the feeler and thereby avoid injurious contact with the filling, while permitting the feeler itself to call for the change of filling when that in the shuttle is substantially exhausted.

What is claimed is:

1. In a feeler mechanism for looms, the combination of the lay, filling detecting mechanism mounted in front of the lay, means for moving the detecting mechanism frontwardly at a lower speed than the approaching lay on a detecting beat that the filling may be engaged by the detecting mechanism with non-injurious contact, and means for changing the loom operation when the detecting mechanism detects substantial exhaustion of filling.

2. In a feeler mechanism for looms, the combination of a feeler mounted in front of the lay to engage the filling on detecting beats as the lay approaches the feeler, means controlled by the feeler to effect a change in the loom operation on detection of substantial exhaustion, and means for starting the feeler frontwardly on detecting beats in advance of and at a slower speed than the approaching lay before the feeler engages the filling to avoid injurious impact of the feeler against the filling.

3. In a feeler mechanism for looms, the combination of a feeler mounted in front of the lay to engage the filling on detecting beats as the lay approaches the feeler, means for imparting an initial frontward movement to the feeler on a detecting beat before it is overtaken by the approaching lay that the feeler may engage the filling with non-injurious contact, and means for initiating replenishment of filling.

4. In a feeler mechanism for looms, the combination of a feeler mounted in front of the lay, means for causing the feeler to be moved frontwardly on a detecting beat before the feeler engages the filling and at a slower speed than the approaching lay to engage the filling as the feeler and lay move frontwardly to avoid injurious contact with the filling, and filling replenishing means at the opposite side of the loom controlled in its operation by the feeler.

5. In a feeler mechanism for looms, the combination of a feeler mounted in front of the lay, means for moving the feeler frontwardly on detecting beats as the lay approaches the feeler before the feeler strikes the filling and at a speed less than that of the lay that the feeler may engage the filling

- as the approaching lay overtakes the feeler, and means controlled by the feeler for effecting replenishment of filling.
6. In a feeler mechanism for looms, the combination of a feeler mounted in front of the lay, means normally acting to move the feeler to its rearward feeling position, means for starting the feeler frontwardly in front of the approaching lay before the feeler strikes the filling that the feeler may engage the filling with non-injurious contact, and means controlled by the feeler for effecting a change in the loom operation.
7. In a feeler mechanism for looms, the combination of a feeler, means normally acting to move the feeler to its rearward feeling position, lay actuated means for starting the feeler frontwardly from its rearward position before the feeler strikes the filling that the feeler may engage the filling during frontward movement of the feeler with non-injurious contact, and means controlled by the feeler for effecting a change in the loom operation.
8. In a feeler mechanism for looms, the combination of a feeler to detect the condition of the filling in the shuttle and effect a change in the loom operation on substantial exhaustion thereof, and means independent of the filling including a lay actuated cam and projection connected to the feeler for imparting an initial frontward movement to the feeler on a detecting beat before the feeler engages the filling and then permitting the feeler to engage the filling during the initial frontward movement of the feeler to relieve the filling from injurious impact by the feeler.
9. In a feeler mechanism for looms, the combination of a feeler mounted for movement towards and from the front of the loom, a cam, a part connected to the feeler and engaged by the cam when the feeler is in rearward feeling position, and means for actuating the cam before the feeler strikes the filling on a detecting beat to start the feeler frontwardly for engagement by the filling during such frontward movement of the feeler.
10. In a feeler mechanism for looms, the combination of a feeler mounted for movement towards and from the front of the loom, a cam, a part connected to the feeler and engaged by the cam when the feeler is in rearward feeling position, and an arm connected to the cam and actuated by lay movement to withdraw the feeler frontwardly before the feeler strikes the filling that the feeler may engage the filling as the feeler is being withdrawn frontwardly.
11. In a feeler mechanism for looms, the combination of a feeler mounted in front of the lay and comprising an impinging and a penetrating member, means normally acting to move the feeler to its rearward feeling position for engagement with the filling, means for starting the feeler frontwardly from its rearward feeling position in front of the approaching lay at a speed less than that of the lay that the feeler may engage the filling with non-injurious contact, and means controlled by the penetrating member of the feeler for effecting replenishment of filling.
12. In a feeler mechanism for looms, the combination of a feeler comprising an impinging and a penetrating member, means for locking the impinging member projected beyond the penetrating member, means for starting the feeler frontwardly before the impinging member strikes the filling on a detecting beat to permit engagement with the filling during frontward movement of the feeler, means for unlocking the impinging member when the filling is nearly exhausted, and means actuated by the penetrating member for effecting replenishment of filling.

In testimony whereof, I have signed my name to this specification.

MELVIN L. STONE.
